UNITED STATES PATENT OFFICE

2,441,000

OUTBOARD MOTOR SUPPORT

Daniel A. Armstrong, Minneapolis, Minn., assignor to Scott-Atwater Manufacturing Company, Minneapolis, Minn., a partnership

Application November 16, 1944, Serial No. 563,672

19 Claims. (Cl. 248—4)

1

This invention relates to a device for supporting an outboard motor upon a boat. Such outboard motors are commonly supported upon a bracket which is clamped to the boat transom and has means for supporting the outboard motor at the rear of the boat.

It is an object of this invention to provide a device for supporting an outboard motor upon a boat, which device has a motor supporting portion swingable in a vertical plane together with novel and efficient means for limiting the swinging movement and determining the position of said portion.

It is a further object of the invention to provide a device for supporting an outboard motor upon a boat comprising a bracket so formed that it can be streamlined and made of pleasing appearance together with novel and efficient means for limiting the swinging movement of the outboard motor and holding it in varied positions comprising easily operable parts which are permanently attached so that there is no danger of the same being mislaid or dropped in water.

It is another object of the invention to provide a device for supporting an outboard motor upon a boat comprising a member adapted to be attached to the boat transom, a member pivoted to said bracket about a horizontal axis adapted to carry said motor, one of said members being provided with a plurality of spaced recesses, a third member carried by said last mentioned member and adapted to be disposed in any one of said recesses so as to hold said second member in different positions.

It is still another object of the invention to provide a device for supporting an outboard motor upon a boat comprising a member adapted to be clamped to the boat transom, said member comprising laterally spaced portions, a second member pivoted to said bracket adjacent the top thereof to swing about a horizontal axis and between said portions, said portions having a plurality of transversely aligned open ended recesses therein and an elongated member extending between said portions and adapted to be disposed in any one of said recesses to limit the swinging movement of said second member and determine its position.

It is more specifically an object of the invention to provide a device for supporting an outboard motor upon a boat comprising a member adapted to be clamped to the boat transom, said member comprising laterally spaced portions, means connecting said portions and holding the same in fixed relation, a second member

2

pivoted to said first mentioned member about a horizontal axis and adjacent the top thereof so as to swing toward and from said first mentioned member and between said portions, each of said portions having a plate secured therein, said plate having an elongated slot therein with a plurality of open ended recesses opening thereto, said plates and recesses being transversely aligned in said spaced portions, a pin extending between and through said plates and disposable in any pair of aligned recesses and adapted to be engaged by said second member to position the same.

It is still further an object of the invention to provide such a device as set forth in the preceding paragraph, said recesses being arranged in a line making a comparatively small acute angle with the vertical and said portions having chambers adjacent said plates, said pin having heads at its ends disposed in said chambers so that removal thereof from said first mentioned member is prevented whereby said pin cannot be mislaid or dropped in the water.

Another object of the invention is to provide a device for supporting an outboard motor upon a boat comprising parts constructed and arranged to be made by die casting.

It is also an object of the invention to provide a device for supporting an outboard motor upon a boat comprising a bracket having spaced parts each comprising a hollow arch constructed so that reinforcing members commonly used in the prior art are unnecessary.

These and other objects and advantages of the invention will be fully set forth in the following description made in connection with the accompanying drawings in which like reference characters refer to similar parts throughout the several views and in which:

Fig. 1 is a view in front elevation of said device, a portion thereof being broken away and portions being shown in vertical section;

Fig. 2 is a view in side elevation, certain parts being broken away and others shown in vertical section;

Fig. 3 is a substantially horizontal section taken on line 3—3 of Fig. 8 as indicated by the arrows;

Fig. 4 is a substantially vertical section taken on a plane indicated by line 4—4 of Fig. 8 as indicated by the arrows but showing both sides and connecting portions thereof of the device;

Fig. 5 is a vertical section taken on line 5—5 of Fig. 2 as indicated by the arrows;

Fig. 6 is a horizontal section taken on line 6—6 of Fig. 2 as indicated by the arrows;

Fig. 7 is a view in side elevation of one portion of said device looking at the outer side thereof;

Fig. 8 is a view in side elevation of one of said portions looking at the inner side thereof;

Fig. 9 is a view similar to Fig. 8 with certain parts removed;

Fig. 10 is a view of a plate used in said device;

Fig. 11 is a vertical section taken substantially on line 11—11 of Fig. 9;

Fig. 12 is a vertical section taken on line 12—12 of Fig. 9;

Fig. 13 is a vertical section taken on line 13—13 of Fig. 9;

Fig. 14 is a vertical section on line 14—14 of Fig. 9; and

Fig. 15 is a vertical section taken on line 15—15 of Fig. 9, the sections of Figs. 11 to 15 being taken as indicated by the arrows.

Referring to the drawings a device is shown comprising a bracket 15. Said bracket comprises laterally spaced portions 15a. Each portion 15a has an inner part 15b and an outer part 15c. Parts 15b and 15c are joined at their upper ends and are spaced to form a recess or opening 16 in which the boat transom or end of the boat will be disposed. Each portion 15b has a hub or boss 15o at its lower end which is tapped to receive a clamping screw 17 equipped with a head 18 adapted to engage the inner side of the boat transom. The screws 17 are flattened at their outer ends and disposed between the bifurcated ends of a handle member 19 to which they are pivoted by the pivot rivets 20. The inner portion of the parts 15b are curved in vertical cross section as shown in Fig. 2, and are also curved about substantially horizontal radii at their outer sides as shown in Fig. 1. The portions 15a at their lower ends are provided with grooves 15ce in which is disposed a plate 21 which extends between portions 15a and secures the same together in fixed relation at their lower ends. Plate 21 is secured at each end by a pair of countersunk headed screws 22, one of which extends into a projection 15cc and both of which extend into a lug 15cd in the rear of groove 15ce (see Figs. 13 and 15). The upper parts of portions 15a are horizontally bored to receive a connecting or tie bolt 23 as clearly shown in Figs. 1 and 5. Said portions 15a are provided with recesses 15d to receive the head and nut respectively of bolt 23. Disposed between portions 15a is a member 25 bored adjacent its upper inner end to receive bolt 23 and having lateral faces engaging faces 15e at the inner side of the parts 15a. Member 25 has a hub 25a at its lower end bored to receive a portion of the outboard motor and has a hub 25b at its upper end which is likewise bored to receive a portion of said motor. The outboard motor is thus swingingly carried on member 25, which member is swingable on bolt 23 and about the axis thereof. The lower portion of bracket 25 moves between the portions 15c of member 15 as clearly shown in Figs. 1 and 2. The portions 15b are provided with grooves or slots 15f at their forward adjacent parts and a plate 26 extends between members 15a, the same being curved on the same curvature as the front of portions 15b, said plate having tongues 26a disposed in the grooves 15f. The lower end of plate 26 extends beyond slots 15f, the same being disposed between the side portions 15a and curved as shown in Fig. 8. It will be noted that tongues 26a do not extend

to the bottom of slots 15f. If it is necessary to move the upper ends of portions 15a together or take up wear between said ends and member 25, this can be done by tightening the nut on bolt 23. The grooves 15f will thus accommodate this movement. The curvature of the portion of plate 26 between slots 15f and the curvature at the upper ends of portions 15a give a nice streamlined structure and one giving a pleasing and ornamental effect. The forward side of portion 15c as shown in Fig. 2, extends substantially vertically and this will engage the outer side of the boat transom. Small rounded projections 15g may be provided at said side for engaging the boat or transom. The bore or hole 15m which receives bolt 23 is surrounded by a lug or boss 15n. Lugs 15k are provided on portions 15a arranged to be engaged by lugs 25d on member 25 to limit the upward swinging movement of the latter. Each portion 15a is recessed on its inner side to receive a plate 28. Each portion 15a as clearly shown in Figs. 7 and 8 is provided with spaced lugs or bosses 15p in which the recesses 15pa for plates 28 are formed.

The member 15a also has transversely extending ribs 15q and 15r. A rib 15s also extends from boss 15n transversely of the bracket. A rib 15t extends from one of the portions 15p to the side of the bracket. As shown in Fig. 1, the member 15a has its inner side 15u substantially in one plane. The upper side of lug or hub 15o extends in one plane which is substantially perpendicular to said side or plane of member 15a as shown in Fig. 11. The sides of the rib 15q are also substantially perpendicular to said side or plane as shown in Fig. 11. The sides or ribs 15s, 15r and 15t are also substantially perpendicular to said side or plane and the sides of boss 15n are also substantially perpendicular to said side or plane. The sides of the ribs or bosses 15p are also substantially perpendicular to said side or plane as shown in Fig. 13. The inner sides or walls of the portions 15b and 15c of the bracket are also substantially perpendicular to said open side and said plane adjacent said open side. This is clearly shown in Figs. 12, 14 and 15. It will be seen that there are a plurality of recesses formed by the walls of portions 15b and 15c and the ribs 15q, 15s, 15r, 15t and the bosses 15n and 15p. The inner sides or walls of these recesses are substantially perpendicular to the open side of the bracket and said plane or converge somewhat as they move away from said plane. This structure enables the bracket 15a to be made by a die casting process. The cores of the die can be withdrawn toward the open side of the bracket. The sides of ribs 15q, 15s, 15r and 15t converge slightly toward the open side of the bracket and the walls of said recesses as shown in Figs. 11 to 15 converge inwardly so that said cores of the die can be conveniently withdrawn and withdrawn unobstructedly. The open side of the bracket is seen in Figs. 8 and 9. The observer is looking into the open side of the bracket in said figures. The bracket is particularly constructed and arranged therefore, to be made by die casting.

It will also be seen that the top wall of portion 15b adjacent the open side of the bracket is formed on a curve of general semi-cylindrical form. As shown in Fig. 1, the outer surface of the bracket is also formed on a substantially semi-cylindrical curve as seen from the front or rear. The upper part of the bracket is thus of hollow arch or dome shape. This forms a very strong

structure and it is unnecessary to have reinforcing members, such as steel inserts, cast into the structure of the bracket as has been the practice in the prior art. The arch or dome formation together with the integral ribs described, give ample strength for the rugged use to which the bracket is put.

Plate 28 has lugs at each end provided with holes 28a through which pass the screws 29 for holding said plates in the recesses 15a in lugs or bosses 15p. A lock washer 30 preferably is disposed beneath the head of each screw 29. Each plate 28 is provided with an elongated slot 28b and with a plurality of open ended recesses 28c which open into the slot 28b. Recesses 28c extend downwardly at an angle to the sides of plate 28 and said recesses have rounded lower ends. An elongated member or pin 32 extends between and through the plates 28 as clearly shown in Fig. 4. Each portion 15a has a recess or chamber 15h beneath or at the outer side of plate 28 and pin 32 has portions or heads 32a disposed at the remote sides of plates 28 and in the respective chambers 15h. Member 25 has spaced ribs 25c at its front side adapted to engage pin 32 as shown in Fig. 2. This limits the inward swinging movement of member 25 or its movement toward member 15 and determines the position of member 25. The recesses 28c are in a line extending parallel to the sides of plate 28 and making a comparatively small acute angle with the vertical as shown in Fig. 2, or with the inner rectilinear front side of portion 15c. The plates 28 are transversely aligned in the portions 15a and the recesses 28c are respectively transversely aligned. The axis of the drive shaft of the outboard motor coincides with or is parallel to the aligned axes of the bores in hubs 25a and 25b. The pin 32 can be readily removed from one recess 28c and placed in any other recess. It will be readily seen that the bracket 25 and the axis of hubs 25a and 25b will be positioned at different angles to the vertical when pin 32 is in different recess 28c.

In operation the motor as stated, will be carried on bracket 25 and will preferably have the drive shaft thereof coincident with or parallel to the axis of bores in the hubs 25a and 25b. When the motor is to be attached to the boat, bracket 15 will be disposed so that the rear of the boat or the boat transom is disposed in the recess 16 and the front of portion 15c will engage the outer surface of the boat end or transom. The operator will then rotate the handles 19 and move the screws 17 so that members 18 are brought against the inner side of the boat end or transom. The member 15 can thus be very firmly attached to the boat. Bracket 25 and the motor can be swung upwardly about the axis of bolt 23 to lift it from the water, give relief if an obstruction is encountered or in order to position the motor in the desired position or have its drive shaft at the desired angle. The pin 32 can be very quickly disposed in any one of the recesses 28c. The front side of bracket 25 engages said pin and it will be apparent that the angle of bracket 25 will vary according to the position of pin 32. It is only necessary to swing bracket 25 and the motor away from the pin a short distance in order to move the pin into another one of the recesses 28c. The slots 28b and recesses 28c are so proportioned that pin 32 cannot be withdrawn from plates 28 or thus from member 15 so that there is no danger of the same being mislaid or dropped in the water. It is ex-

tremely desirable to have such an attached member. In prior constructions it has been common to use a bolt or pin equipped with wing nuts or cotter pins. Such nuts and cotter pins must be removed to change the position of the bolt and it is quite common for these parts to be mislaid or dropped in the water. Applicant's pin 32 can be very easily and quickly changed in position without being removed from the member 15 and as stated, there is no danger of the same being lost or dropped. The chambers 15h are of sufficient width to give ample clearance for movement of pin 32. Should it become necessary to take up any looseness or wear between members 15 and 25 the nut on bolt 23 can be tightened. The space left between the end of tongue 26a and the bottom of groove 15f and between the shoulder formed by tongue 26a and the inner surfaces of members 15a permits such a take up adjustment. The portions 15a are provided with strengthening ribs on their inner sides and have their outer sides formed in a continuous streamlined surface. A bracket having high utility is thus produced, and the same has a pleasing appearance. The outer smooth surface also acts to prevent the accumulation of oil, dirt and grease.

The curved lower end of plate 28 forms a handle for carrying the motor. It will be seen that said plate can be gripped between portions 15a and will thus form a comfortable and convenient handle.

It will be apparent that the device will have a high degree of utility for the purpose intended. The same has been amply demonstrated in actual practice and found to be very successful and efficient.

It will of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

45. This application is a continuation in part of applicant's co-pending application filed July 27, 1944, on "Outboard motor support," S. N. 546,864, now abandoned.

What is claimed is:

50. 1. A device for supporting an outboard motor having in combination, a member having a portion constructed and arranged to be attached to a boat transom, a second portion pivoted to said portion and adapted to carry said motor, said second portion being swingable toward said first mentioned portion, a second member loosely carried by one of said portions and engaged by the other portion to limit said swinging movement of said second portion toward said first mentioned portion, one of said portions having a plurality of spaced open ended recesses therein, said second member constituting a movable separate member disposable in any one of said recesses.

55. 2. The structure set forth in claim 1, said second member comprising portions preventing complete removal thereof from said portion in which it is carried.

60. 3. A device for supporting an outboard motor having in combination, a member adapted to be attached to a boat and comprising laterally spaced portions having recesses in their adjacent sides, means connecting said portions and holding the same in fixed relation, a second member pivoted adjacent the top of said first mem-

tioned member and swingable toward the same and between said portions, a plate secured in each of said portions over said recesses so that a chamber is formed under said plate, said plate having a slot therein and a plurality of spaced open ended recesses opening into said slot, said recesses being transversely aligned in said portions, an elongated member extending between and through said plates having portions disposed in said chambers respectively and movable in said slots so as to be disposed in any one of said recesses for limiting the swinging movement of said second member.

4. A device for supporting an outboard motor having in combination a member adapted to be attached to a boat and comprising laterally spaced portions, means connecting said portions and holding the same in fixed relation, a second member pivoted adjacent the top of said first mentioned member and swingable toward the same and between said portions, a plate secured in each of said portions, said plate having a slot therein and a plurality of spaced open ended recesses opening into said slot, said portions having chambers in the rear of said plates, an individually movable elongated member extending between and through said plates and movable in said slots so as to be disposed in any one of said recesses, said elongated member having means at its ends disposed in said chambers respectively preventing removal of the same from said plates and portions whereby the same will not be mislaid or dropped in the water.

5. A device for supporting an outboard motor having in combination, a member adapted to be attached to a boat transom and comprising laterally spaced portions, each of said portions having a curved surface extending from adjacent its top to its lower end at the inner portion thereof and having a part extending downwardly along the outer side of said transom, said member including a plate extending between said curved surfaces and curved similarly thereto, a clamping and securing means extending between said first mentioned portions holding the same in fixed relation, means connecting said first mentioned portions at the lower end of said last mentioned portions, a plate carried in each of said first mentioned portions disposed in said part at the inner side thereof, said plates having slots therein with open ended recesses opening into said slots, said first mentioned portions having chambers at the outer sides of said plates, a pin extending between and through said plates and having heads thereon at the remote sides of said plates, said heads preventing removal of said pin from said slots, said pin being movable into any one of said recesses, a second member pivoted to said first mentioned member and swingable toward the same and between said first mentioned portions, said second member being adapted to engage said pin for limiting the swinging movement of said second member and determining its position.

6. A device for supporting an outboard motor having in combination, a member adapted to be attached to a boat end or transom, said member comprising laterally spaced portions, a second member pivoted adjacent the top of said member and between said portions, a clamping means holding said portions together, said second member being swingable in a vertical plane, a cover plate extending between said portions and having interengaging relation therewith, said portions being laterally movable relatively to said plate to permit take-up by said clamping means.

7. The structure set forth in claim 6, said portions having grooves at their adjacent sides and said plate having edge portions disposed in said grooves.

5 8. A device for supporting an outboard motor having in combination, a member adapted to be secured to a boat and comprising laterally spaced portions, a second member disposed between said portions, a pivot bolt connecting said members adjacent the upper end of the same, said members having engaging lateral faces about said bolt, a cover plate extending between said portions having interfitting engagement therewith, said portions being movable laterally relatively to said plate to permit take-up by said bolt.

15 9. A device for supporting an outboard motor having in combination, a member adapted to be attached to a boat end or transom for supporting said motor, said member comprising laterally spaced portions, each portion having a part disposed inwardly of said boat end or transom and a part extending downwardly along the outer side of said boat end or transom, a cover plate extending between said first mentioned parts of said 20 portions and means for holding said portions in fixed relation said portions being movable toward each other and relatively to said plate.

25 10. A bracket for supporting an outboard motor upon a boat having a portion adapted to be disposed at one side of a boat transom and a portion adapted to be disposed at the other side of said transom, said portions being integrally connected, said bracket being closed at one side and having an open side and having a plurality of 30 recesses therein, the walls of said recesses being substantially perpendicular to said open side adjacent the same and converging inwardly from said open side so that said bracket may be made as a die casting and the cores of the die unobstructedly withdrawn from said recesses toward said open side.

35 11. A bracket for supporting an outboard motor upon a boat having a portion adapted to be disposed at one side of a boat transom and a portion 40 adapted to be disposed at the other side of said transom, said bracket being of integral form and having a curved wall and an open side disposed substantially in one plane, ribs extending across said bracket and forming with the walls thereof a plurality of recesses, the walls of said recesses converging inwardly from said inner side whereby said bracket can be made as a die casting and the cores of the die withdrawn toward said open side.

45 12. A bracket for supporting an outboard motor upon a boat comprising a hollow shell having an open side, said bracket having its top wall curved forwardly and rearwardly and also curved transversely, said bracket having a plurality of bosses therein and a plurality of transversely extending 50 ribs, said bosses and ribs forming recesses, the walls of said recesses being substantially perpendicular to said open side adjacent said side and converging inwardly from said side so that said bracket may be made as a die casting and the cores for said recess unobstructedly withdrawn toward said side.

55 13. A bracket for supporting an outboard motor upon a boat comprising a hollow shell having a substantially flat open side, said bracket having ribs and bosses therein forming a plurality of recesses, said recesses having walls extending inwardly from said open side and converging inwardly from said open side whereby said bracket 60 can be formed as a die casting and the cores for

said recesses unobstructedly withdrawn toward said open side.

14. A device for supporting an outboard motor having in combination, a member adapted to be attached to a boat end or transom, said member comprising laterally spaced portions, a member pivoted to said member adapted to support said motor, a plate extending between and engaging said portions, means for holding said plate and portions together, said plate being reversely curved at its lower end between said portions to constitute a handle for carrying said motor.

15. A bracket for supporting an outboard motor upon a boat having laterally spaced portions, each portion having a platelike part of general inverted U-shape, the sides of which are adapted to be disposed at the opposite sides of a boat transom, means carried by one of said sides for engaging and clamping the bracket to said transom, a plate spaced from said part and extending thereabout in substantially semi-cylindrical form, said plate also being curved laterally at the outer sides of said first mentioned portions thereby having a hollow arch or dome form, spaced ribs extending from said plate to said part and disposed at angular relation, one side of each of said first mentioned portions being open.

16. The structure set forth in claim 15, said open side of each of said portions being disposed substantially in the same plane.

17. A bracket for supporting an outboard motor upon a boat comprising spaced portions each having an open side facing each other, each portion having a central plate-like part of general inverted U-shape, the sides of which are arranged to be disposed at opposite sides of a boat transom, means extending through one of said sides for engaging said transom to clamp said bracket thereto, a plate extending about and spaced from said part and being substantially of inverted U-shape, said plate being curved to have a convex surface at the remote sides of said portions, whereby each of said portions has a hollow dome-shaped form, means connecting said portions adjacent the top of the same and adjacent said plate, and means for connecting said portions adjacent the bottom of the same.

18. A device for supporting an outboard motor having in combination, a member having a portion with a slot therein constructed and arranged to receive a boat transom, clamping means carried by said portion for clamping said member to said transom, a second portion pivoted to said portion and adapted to carry said motor, said second portion being swingable toward and from said first mentioned portion, a second separate

and individually movable member loosely carried by and retained in one of said portions and engaged by said second portion to limit said swinging movement of said second portion toward said first mentioned portion, one of said portions having a pair of elongated slots therein with a plurality of open-ended recesses in one side thereof, said second member being freely movable so that it can be disposed in any one of said recesses 10 without being removed from the portion in which it is carried, said recesses being arranged in a line making an acute angle with the vertical.

19. A device for supporting an outboard motor having in combination, a member adapted to be attached to a boat and having an opening therein for receiving a boat transom, said member comprising means for clamping the same to said transom, said member comprising laterally spaced portions and a plate disposed between said portions at its inner end, means securing said portions together and holding the same against said plate in fixed relation, a second member pivoted to said first mentioned member and swingable toward the same, said second member being constructed and arranged to carry said motor, plates secured in the adjacent sides of said portions, said plates having elongated slots therein with a plurality of spaced open-ended recesses at one side of said slots respectively and opening into said slots, said plates and recesses being in transverse alignment in said portions, a separate and individually movable pin extending between and through said plates and movable in said slots so as to be disposed in any one of said recesses and to be engaged by said second member for limiting the swinging movement thereof, said pin having means thereon preventing its removal from said plates and first mentioned member whereby it cannot be mislaid or dropped into the water while being moved from one pair of recesses to another pair, said recesses being arranged in a line making an acute angle with the vertical.
